[57] CLAIM

The ornamental design for the electrical outlet unit, as shown and described.

DESCRIPTION

FIG. 1 is a perspective view of an electrical outlet unit according to the invention;

FIG. 2 is a rear view of the electrical outlet unit of FIG. 1; FIG. 3 is a side view of the electrical outlet unit of FIG. 1, both sides being identical;

FIG. 4 is a top view of the electrical outlet unit of FIG. 1; FIG. 5 is a front view of the electrical outlet unit of FIG. 1; and,

FIG. 6 is a bottom view of the electrical outlet unit of FIG. 1.

The broken line showing is included for the purpose of illustrating environmental structure only and forms no part of the claimed design.
